UNITED STATES PATENT OFFICE.

JOSEPH PATER WIATT, OF SYDNEY, NEW SOUTH WALES, AUSTRALIA, ASSIGNOR TO
K. F. B. FOUNDRY LIMITED, OF SYDNEY, NEW SOUTH WALES, AUSTRALIA, A
CORPORATION OF NEW SOUTH WALES.

GAS STOVE OR OVEN.

Application filed June 1, 1926, Serial No. 113,045, and in Australia March 9, 1926.

This invention relates to stoves or ovens, heated by a combustible gas. The object of the invention has been to overcome certain disadvantages existing in such ovens as now 5 constructed; more especially in conserving the heat within the oven, and, minimizing the possibility of the gas burners being extinguished through back draught from the flue pipe and consequent danger of explosion of 10 the escaping gas.

The improvements comprise a passage in the oven distinct from the oven proper. Connected to the passage is a waste gas outlet pipe outside the oven which leads to an upwardly 15 extending flue forming together a downward and upward bend. At or adjacent to the connection of the flue with the outlet pipe at the underside of the bend, is an air inlet, which 20 may have a deflecting plate in order to direct the air up the flue.

When the heating gases rise in the oven they pass through the passage towards the waste gas outlet. A comparatively slow movement of these gases takes place, for the 25 reasons that the gases in the passage being hot tend to offer resistance to the escape of the heated gases within the oven and the up draught in the flue pipe is partly air drawn through the inlet outside the oven, the effect 30 being that the heated gases draw in a minimum of cold air through the usual air inlet holes or openings at the bottom of the oven, resulting in the heated gases remaining for a longer period therein.

35 In order that my invention may be more clearly understood, I will now refer to the drawings herewith in which practical embodiments thereof are illustrated.

Figure 1, is a sectional elevation of the preferred form of stove constructed in accordance with the invention, the arrows showing the direction of flow of the gas and air, while

Figure 2, is a plan view on line 2—2, Figure 1.

45 Figure 3, is a part perspective view illustrating the air inlet into the flue pipe.

Figure 4, in a sectional elevation showing an ordinary oven to which the invention is applied.

50 Referring to Figures 1, 2, and 3, 10 is a stove with door 11, the sides 12, back 13, and top 14 being preferably double jacketed and packed with heat resisting material such as mineral wool, or asbestos or the like. 15 is the

usual hot plate. 16 is a passage which extends from adjacent the bottom where it is closed to near the top of the stove, the upper end thereof being open to the stove. A waste gas outlet 17 is connected to the stove 10 being open to the passage or space formed by a partition 18, and to an upward flue 17^A. A deflecting plate or baffle 19 is provided in the outlet 17 so positioned that it will facilitate air being drawn in through the opening 21 and assist in preventing excess of air flowing 65 past the burners 20 and through the stove 10.

In operation there is a comparatively slow movement of the heated gases in the stove owing to the fact that the hot gases in the passage 16 tend to resist the escape of heated 70 gases from the oven and that the up-draught in the flue pipe 17^A partly draws in air through the inlet or opening 21, consequently the heated gases draw in a minimum of cold air through the air inlet holes or openings at 75 the bottom of the oven, and, as the stove is preferably jacketed or made heat resisting, a large saving in gas consumption is obtained.

The burners 20—20 may be turned off after the stove has reached a predetermined temperature and the heat retained in the stove for a considerable time.

In Figure 4, 30 is an ordinary gas oven having an inner crown plate 31 and an outer crown plate 32 leaving a space or passage 33 85 into which the waste heated gases pass through the usual openings, as 34. From the end of said passage 33 is an outlet 35 having a downward and upward bend outside the oven and to the upward part is connected the flue 90 36. In the underside of the bend is an air inlet 37 which may have a deflector plate or baffle 38.

I claim:

A gas stove comprising a structure including an oven chamber having air inlet openings in the bottom, a gas burner in said chamber, an outlet duct leading from the upper portion of said chamber and an upwardly directed flue into which said outlet duct discharges, said flue having an elbow provided with an air inlet opening and also having a fixed baffle at the side of said air inlet opening nearest the gas intake end of said flue, and extending nearly across said flue. 105

JOSEPH PATER WIATT.
